Fred A. Heidenfelder, Chicago, Ill., assignor to
The American Laundry Machinery Company,
Cincinnati, Ohio, a corporation of Ohio

Application February 9, 1931, Serial No. 514,391

7 Claims. (Cl. 192—131)

My invention relates to a pressing machine for use in shaping and finishing garments for the laundry as well as for the garment trade.

One object of my invention is to provide a 5 pressing machine that is simple in construction and yet durable, embodies means for creating garment pressing pressure between the pressing members, and also safety means for eliminating danger of injury to an operator's hands by 10 their being caught between the pressing members during the cycle of movement of the movable pressing member in the pressing operation.

To attain the above object, my invention contemplates the provision of a pressing machine 15 embodying relatively movable pressing members consisting of, in this instance, a movable head and a stationary bed together with means for bringing the pressing members into and out of cooperative pressing relation including a power 20 unit that may take any desired form but is shown as a piston and cylinder construction having suitable operating connection with the lever on which the pressing head is mounted. It also contemplates provision of control means for the 25 power unit embodying foot treadle mechanism for operating the usual fluid pressure valves, means independent of the power unit for resisting the effect of the power unit on the pressing members and embodying a latch or lock adapted 30 to be effective on some part of the operating parts of the power unit or operating connections between the power unit and the movable head to resist the effect of the power unit in closing the 35 press by bringing the pressing members into cooperative relation, and two-hand control means for rendering such latch or lock ineffective. As hereinafter disclosed, the latch or lock comprises two separate latches or locks adapted to engage 40 one of the links of the toggle connection between the power unit and the head lever to prevent movement of the toggle to straightened position unless both of the latches or locks are moved out of latched position, and an operating handle for each latch or lock, the two operating handles 45 being spaced apart on the operator's side of the pressing machine to such an extent that both of the operator's hands are necessarily simultaneously used to move both of the latches or locks out of latched position at the same time so that the 50 power unit may be effective to bring about pressing engagement of the pressing members. The resisting means is such that should one latch or lock only be moved to unlatched position, the 55 power unit will be ineffective to move the pressing

members into pressing engagement and should one latch be released after the press is in operation, movement of the pressing head toward the pressing bed will be stopped prior to the head reaching such position relative to the bed that 60 an operator's hand might not safely be withdrawn from between the pressing members.

Various other objects and advantageous features of my invention will be seen in the following description and one embodiment thereof may 65 be seen in the accompanying drawings wherein similar characters of reference designate corresponding parts, and wherein:

Fig. 1 is a side view of a pressing machine constructed in accordance with my invention with 70 the press in open position; Fig. 2 is a view similar to Fig. 1 but showing the press in closed position; Fig. 3 is a cross sectional view taken on the line 3—3 of Fig. 2; Fig. 4 is a view of the valve, operating mechanism; and Fig. 5 is a side view 75 of the treadle means for closing the intake and opening the exhaust valves that control the operation of the power unit.

Referring to the drawings, particularly Figs. 1 and 2 thereof, the type of press shown comprises a frame 1 having an upwardly extending portion 2 on which a head lever or pressure arm 3 is pivotally mounted as at 4. A pedestal 5 on the frame 1 supports a lower pressing member or buck 6 covered by the usual padding and the 85 head lever or pressure arm 3 carries an upper pressing member or head 7 to which heat may be supplied by any well known means.

The means for moving the pressing head 7 into and out of engagement with the pressing bed 6 90 embodies a power unit that takes the form of a cylinder and piston construction embodying a cylinder 8 having a piston 9 therein, the piston normally being held in its rearwardmost position by a spring 10 surrounding the piston rod 11 95 and moved to its operated position against the resistance of the spring 10 by fluid pressure from a line 12 and under the control of a suitable inlet valve 13. An exhaust valve 14 is also provided and the control of these valves will be 100 hereinafter described. Operative connection between the power unit and the head lever 3 is made by a plurality of links 15 and 16 that make up the well known toggle mechanism, one of the links being connected to the piston rod 11 as at 105 17 whereby outward movement of the piston will cause straightening of the toggle and engagement of the pressing members 6 and 7 for the pressing operation. Movement of the piston in the other direction will cause breaking of the tog- 110

gle as shown in Fig. 1 and separation of the pressing members.

As hereinbefore stated, the control means for movement of the piston 9 in the cylinder 8 to bring about cooperative pressing relation between the pressing members 6 and 7 consists of an inlet valve 13 and an exhaust valve 14. Such inlet valve may be of any desired type but is preferably of the slide valve variety embodying a sliding closure (not shown) and a stem 18 by means of which the closure may be reciprocated to selectively open and close the fluid pressure inlet port. Likewise, the exhaust valve 14 may be of any well known type but is preferably of the type embodying a rotating closure or a closure that moves in an arcuate path.

The control means for the inlet and exhaust valves embodies two foot treadles 19 and 20 pivotally mounted on the frame and connected together by means of links 21 and 22 and a walking beam arrangement 23 that is rigidly mounted on a rotating or oscillating valve closure operating rod 24. The connection between the foot treadles 19 and 20 is such that downward movement of one foot treadle will result in upward movement of the other and vice versa and the arrangement is such that downward movement of one foot treadle opens the inlet valve 13 and closes the exhaust valve 14 whereby fluid pressure is admitted to the cylinder and piston construction just described to move the piston 9 to its operative position and thereby effect engagement of the pressing members 6 and 7. Downward pressure on the other foot treadle will result in closure of the inlet valve 13 and opening of the exhaust valve 14 whereby the piston is returned to its normal position by means of the spring 10 and disengagement of the pressing members 6 and 7 is effected, as shown in Fig. 1.

The operating connection between the foot treadle 19 and the inlet valve 13 consists of an arm 25 pivotally mounted on the frame 1 and adapted to be moved forward and backward to and from the stem 18 of the inlet valve to move the valve to closed position or to permit it to be moved to open position. The arm 25 here shown has a cam surface 26 of the arm 25 that engages the outermost end 27 of the foot treadle 19, such engagement being effected by a spring 28. Referring to Figs. 1 and 2, it will be seen that downward movement of the foot treadle 19 will move the arm 25 to the left to bear against the stem 18 of the inlet valve closure means as shown in Fig. 2 and move the valve to, in this instance, open position. Upward movement of the foot treadle 19 will result in the parts taking the position shown in Fig. 1 wherein the inlet valve 13 will be closed.

In accordance with my invention, a latch or locking means is provided, together with control means therefor, for preventing, when desired, movement of the toggle, made up of the links 15 and 16, to straightened position to bring about engagement of the pressing members. As shown in Figs. 1, 2 and 3, the latch or locking means includes two individual and independent arms 29 pivotally mounted at one of their ends as at 30 on opposite sides of the cylinder 8 and provided adjacent their outermost ends with recesses or notches 31 and 32, each arm being provided with two recesses or notches spaced from each other. A pin 33 extends through the toggle link 16 and this pin is adapted to be engaged by recesses or notches 31 and 32 of the arms 29 when the arms are in their lowermost position.

The operating means for the arms 29 consists of rods 34 that extend upwardly from the arms 29 adjacent their pivoted ends, then angularly rearwardly, and then rearwardly substantially parallel to the arms 29, terminating in handles 35 spaced apart in the front of the pressing machine, in such manner that when the handles 35 are both moved downwardly the arms 29 will be raised to disengage the recesses or notches from the pin 33. Due to the fact that the handles 35 are spaced from each other and each handle only operates one of the arms 29, it will be apparent that the use of both of the operator's hands is necessary to unlock the operating mechanism so that the pressing members may be moved into cooperative pressing relation.

In the operation of this apparatus, the handles are first moved downwardly to release the latches and thereby the press operating mechanism by raising the arms 29 that form the latches or locking members, and then the foot treadle 19 is depressed which will cause opening of the inlet valve 13 and closing of the exhaust valve 14 in the manner hereinbefore described whereby fluid pressure will be admitted to the cylinder 8 to move the piston 9 forwardly against the resistance of the spring 10 to straighten out the toggle made up of the links 15 and 16 and move the pressing members 6 and 7 into cooperative pressing relation. However, with my construction, should one of the handles 35 be released before the toggle reaches full straightened position, one of the arms 29 will drop downwardly whereby the pin 33 will be engaged by the recess or notch 31 so that the piston will merely push against the lock but will not be effective to move the toggle to straightened position, as is also the case when the inlet valve is opened and the exhaust valve is closed prior to the use of both of the operator's hands and raising both of the arms or latching members 29. However, in this instance, the pin 33 is engaged by the notches 32. Then, when it is wished to move the pressing members to open position, the foot treadle 20 is depressed which will close the inlet valve and open the exhaust valve as hereinbefore described and the piston 9 will be moved rearwardly under the action of the spring 10 to move the toggle mechanism to the position shown in Fig. 1 and the pressing members to open position. To move the press to open position, it is not necessary to keep the latching members 29 in raised position since the pin 33 will ride past the recess or notch 31 to finally engage the recess or notch 32.

Referring to the drawings and the preceding description, it will be seen that I have provided a pressing machine embodying numerous novel and advantageous features. For instance, I have provided a pressing machine embodying a latching means, in this instance, manually operable, requiring the use of both hands of the operator to release the press operating mechanism so that the pressing members may be moved to pressing engagement. Further, this latching means is such that, should one hand only be employed or should one of the hands be removed from the latching mechanism prior to starting operation of the press or after such operation is started and before the pressing members reach initial engagement, the press operating mechanism will be again locked to prevent engagement of the pressing members. Thus, a safety means independent of the power means is provided for preventing injury to the operator's hands. Various

other advantageous features will be readily apparent.

What I claim is:

1. In a pressing machine, a pair of relatively movable, cooperating pressing members, mechanism adapted when operated to effect engagement and disengagement of said pressing members, means for operating said mechanism, control means for said operating means, latch means for said mechanism normally preventing operation thereof to effect engagement of said pressing members, and hand operable release means for said latch means, said latch means being effective, upon release of said release means prior to engagement of said pressing members, to arrest operation of said mechanism to thereby prevent such engagement of said pressing members.

2. In a pressing machine, a pair of relatively movable, cooperating pressing members, mechanism adapted when operated to effect engagement and disengagement of said pressing members, means for operating said mechanism, control means for said operating means, latch means for said mechanism normally preventing operation thereof to effect engagement of said pressing members, and a pair of widely separated hand operable release means for said latch means, said latch means being effective, upon release of either of said release means prior to engagement of said pressing members, to arrest operation of said mechanism to prevent such engagement of said pressing members.

3. In a pressing machine, a pair of relatively movable, cooperating pressing members, mechanism adapted when operated to effect engagement and disengagement of said pressing members, means for operating said mechanism, control means for said operating means, two independent latch means for said mechanism, each normally preventing operation thereof to effect engagement of said pressing members, and two independent, hand operable release means, one for each latch means, each of said latch means being effective, upon release of its release means prior to engagement of said pressing members, to arrest operation of said mechanism to thereby prevent such engagement of said pressing members.

4. In a pressing machine, a pair of relatively
50 movable, cooperating pressing members, toggle
mechanism adapted when operated to effect en-
gagement and disengagement of said pressing
members and provided with a latch pin, a latch
bar having a shoulder adapted for engagement
55 with said latch pin, said latch bar being adapted,
when its shoulder is in engagement with said
latch pin, to prevent operation of said toggle
mechanism to effect engagement of said pressing
members, and hand means for actuating said
60 latch bar to effect disengagement of its shoulder

with said latch pin to thereby permit said mechanism to effect engagement of said pressing members.

5. In a pressing machine, a pair of relatively movable, cooperating pressing members, toggle mechanism adapted when operated to effect engagement and disengagement of said pressing members and provided with a latch pin, a piston and cylinder structure for operating said mechanism, control means for said power means, a latch bar pivoted on the cylinder of said piston and cylinder structure and having a shoulder adapted for engagement with said latch pin, said latch bar being adapted, when its shoulder is in engagement with said latch pin, to prevent operation of said mechanism to effect engagement of said pressing members and being ineffective to prevent operation of said mechanism to effect disengagement of said pressing members, and hand means for actuating said latch bar to effect disengagement of its shoulder with said latch pin.

6. In a pressing machine, a pair of relatively movable, cooperating pressing members, mechanism adapted when operated to effect engagement and disengagement of said pressing members, said mechanism being provided with a latch pin, means for operating said mechanism, control means for said operating means, a pivotally mounted latch bar having longitudinally spaced shoulders each adapted for engagement with said latch pin, said latch bar being adapted, when a shoulder thereof is in engagement with said latch pin, to prevent operation of said mechanism to effect engagement of said pressing members, and means for actuating said latch bar to effect disengagement of any of the shoulders thereof with said latch pin, said latch bar actuating means requiring for the operation thereof the use of both hands of the pressing machine operator. 100 105 110

7. In a pressing machine, a pair of relatively movable, cooperating pressing members, mechanism adapted when operated to effect engagement and disengagement of said pressing members, said mechanism being provided with a latch pin, means for operating said mechanism, control means for said operating means, a latch bar having two shoulders each adapted for engagement with said latch pin, said latch bar being adapted, when one of its shoulders is in engagement with said latch pin, to prevent the initiation of the operation of said mechanism to effect engagement of said pressing members and being adapted, when its other shoulder is in engagement with said latch pin, to arrest such operation of said mechanism, and hand operable means for actuating said latch bar to effect disengagement of any of the shoulders thereof with said latch pin 115
